(57) **CLAIM**

We claim the ornamental design for portions of central connector post and locking elements associated therewith for cluster box mail delivery receptacles, as shown and described.

DESCRIPTION

FIG. 1 is a perspective view of portions of a central connector post and locking elements associated therewith for cluster box mail delivery receptacles, showing our new design;

FIG. 2 is a front elevational view, shown separately for purposes of illustration, the undisclosed rear is not part of the claimed design;

FIG. 3 is a front perspective view thereof, shown separately for purposes of illustration, the undisclosed rear is not part of the claimed design; and,

FIG. 4 is a front perspective view thereof, shown separately for purposes of illustration, the undisclosed rear is not part of the claimed design.

The broken lines in FIGS. 1 and 2 are for illustrative purposes only and form no part of the claimed design.

1 Claim, 4 Drawing Sheets
